UNITED STATES PATENT OFFICE

FRANCIE ROBERTA GREENE, OF NEW YORK, N. Y., ASSIGNOR TO C. H. D. ROBINS CO., INC.,
OF NEW YORK, N. Y., A CORPORATION OF NEW YORK

DESIGN FOR A DRESS OR SIMILAR ARTICLE

Application filed December 9, 1932. Serial No. 46,401. Term of patent 3½ years.

To all whom it may concern:

Be it known that I, FRANCIE ROBERTA GREENE, a citizen of the United States, residing in the borough of Bronx, city of New York, county of Bronx and State of New York, have invented a new, original, and ornamental Design for a Dress or Similar Article, of which the following is a specification, reference being had to the accompanying drawing, forming part thereof.

The lines appearing in the drawing serve to indicate a contrast of color.

I claim:

The ornamental design for a dress or similar article, as shown and described.

FRANCIE ROBERTA GREENE.
